UNITED STATES PATENT OFFICE.

DAVID J. NEVILL, OF DENVER, COLORADO, ASSIGNOR TO THE STEARNS ROGER MANUFACTURING COMPANY, A CORPORATION OF COLORADO.

CRUSHING MACHINE.

Application filed August 27, 1920. Serial No. 406,295.

To all whom it may concern:

Be it known that I, DAVID J. NEVILL, a subject of George V, King of England, residing at Denver, in the county of Denver and State of Colorado, have invented 5 certain new and useful Improvements in Crushing Machines, of which the following is a specification.

This invention relates to crushing machines and more particularly to machines of the type in which coal and other similar materials are reduced to a uniform size through the medium of a rotating crushing roll.

It is an object of the present invention 15 to simplify the construction and increase the efficiency of a machine of the type mentioned, by the use of a crushing roll of smaller diameter than those usually found in machines of the same character, but rotating at substantially the same peripheral speed.

A further object of the invention is to provide in conjunction with a rotary crushing roll, two cooperating jaws one of which 25 has a circular reciprocating movement with relation to the other for the purpose of breaking the coal prior to its comminution by the crushing roll and of crowding the broken coal into contact with the roll whereby to insure of the machine operating constantly at its full capacity.

Another object of the present invention 35 is to provide an improved means to yieldingly hold the stationary jaw in its operative position and to permit of an adjustment thereof in case it is desired to place the machine in an idle position when the coal fed thereto is of a size not requiring further reduction.

With the above and other objects in view 40 all of which will fully appear in the course of the following description, my invention consists in the construction, arrangement and combinations of parts shown in the accompanying drawings in the two views of 45 which like parts are similarly designated and in which

Figure 1 is a section of the machine taken 50 on a substantially central, vertical plane and

Figure 2 a composite sectional view taken at one side of the central line thereof, on

the line 2—2, and at the other side of the same along the line 3—3 Figure 1.

Referring to the drawings by numerical 55 reference characters 2 designates the frame of the crushing machine, which comprises two parallel side plates 3 interconnected by cross-members 4 and 5.

A peripherally toothed crushing roll 6 60 is rigidly mounted on a shaft 7 which is rotatably supported in journal bearings 8 at opposite sides of the frame. The bearings are slidably supported upon flat surfaces exteriorly of the side plates, and screws 9 65 extending through threaded openings of the cross-member 5 of the frame and acting upon the bearings, are provided to adjust their position for the proper alinement of the roll relative to the elements of the machine with which it cooperates.

Extending upwardly at the forward side of the roll with reference to the direction of its rotation, are two jaws 10 and 12 which 70 cooperate to feed the material to the roll and to subject the same to a primary breaking action.

The jaw 12 has to this end a circular reciprocating movement with relation to the other jaw which while normally stationary, 75 is mounted for adjustment to an inoperative position and is capable of yielding under excess pressure.

The stationary jaw 10 consists of a curved plate reenforced by external ribs, which at 80 its upper end is suspended from bearings 13 on the side plates of the frame by means of axially alined trunnions 14. The bearings in which the trunnions are supported are closed by caps 15 which are removably 85 connected to the side plates of the frame by means of rods 16 extending through alined openings in the plates and the caps, and nuts 17 screwed upon the threaded extremities thereof.

A steel wear-plate 18 set in a recess of the curved lower portion of the jaw 10 extends in close proximity to the periphery of the crushing roll and it is longitudinally grooved to admit the peripheral teeth of 100 the roll which are arranged circumferentially in equidistant rows. The fixed jaw 10 is held in its normal operative position by means of two racks 19 meshing with

pinions 20 on a shaft 21 which is rotatably supported in bearings 22 at opposite sides of the frame of the machine.

The racks 19 are rigidly connected to rods 23 which extend loosely through apertured lugs 24 formed integrally on the under side of the lower portion of the jaw 10.

The yielding connection between the rods and the jaw is provided by means of springs 25 arranged around the portions of the rods extending rearward of the lugs and between two abutment plates 26 and 27. The inner abutment plates 26 are pivotally connected with the lugs through the medium of rounded ribs seated in correspondingly formed recesses, and nuts 28 screwed upon the extremities of the rods in engagement with the other abutment plates 27, cooperate with nuts 29 bearing upon the forward sides of the lugs, to hold the different parts in their normal positions.

A hand wheel 30 at an end of the pinion shaft facilitates its rotation when for the purpose of separating the jaw 10 from the crushing roll to an inoperative position, as shown in broken lines in Figure 1, a longitudinal movement is imparted to the rods through the medium of the racks and pinions.

30 The hand wheel is provided at its periphery with ratchet teeth 31 which are engaged by a gravity dog 32 pivotally mounted at a side of the frame to hold the jaw in its adjusted positions.

35 The racks are slidably supported upon a cross bar 33 of the frame and they are rigidly connected with the respective rods by means of nuts 34 and 35.

40 The moving jaw 12 which extends upwardly from a point forward of the upper portion of the crushing roll, consists of a plate reenforced by external ribs and carrying a steel face plate 36 in a recess at its lower end.

45 The jaw is mounted upon two eccentrics 37 on the shaft of the crushing roll by means of pitman boxes 38 at its lower end. The eccentrics are keyed to the shaft between the ends of the crushing roll and the journal bearings on the frame in which the shaft is supported, and a fly-wheel pulley 39 at one end of the shaft outside the frame provides for its connection with a conveniently located source of motive power.

50 A movable connection between the upper end of the jaw 12 and the frame of the machine, is established through the medium of a toggle 40 which engages at one of its ends a removable bearing block 41 held in a recess of the jaw by a set screw 42 while its opposite end bears upon an abutment block 43 mounted in a recess of the cross member 4 of the frame.

55 The block 43 has to this end a longitudinal bore and a recess through which extends

a screw 44 which is rotatably but longitudinally immovably mounted on the member 4. A nut 45 nonrotatably fitted in the recess of the block is threaded to cooperate with the bolt and by turning the latter through the medium of a wrench applied to its head the block is readily adjusted in either direction.

70 The corresponding adjustment of the toggle 40 regulates the lateral movement of the upper portion of the moving jaw and thereby avoids excessive crushing at the feed end of the machine which, if continued, would cause the material to choke in the lower part of the crushing space.

75 The jaw is held in position against the toggle by means of a pivoted bolt 46 extending through an opening in the cross member of the frame, and a coil spring 47 arranged around the outer portion of the bolt between said member and an abutment plate 48 held upon the threaded end of the bolt by nuts 49.

80 In the operation of the crushing machine the coal is fed between the jaws at the upper end thereof. The circular motion of the moving jaw imparted thereto by the eccentrics on the shaft of the crushing roll, breaks the larger lumps of coal in cooperation with the relatively fixed jaw and at the same time crowds the material into the space between the peripheral surface of the roll and the wear-plate at the lower end of the stationary jaw. The coal is thus continuously fed to the crushing roll in pieces sufficiently small to enter into the gradually narrowing space 90 between the fixed jaw and the toothed surface of the roll and a continuous crushing action is obtained without the use of auxiliary breaking machines or mechanical feeding devices.

95 The crushing stroke of the upper end of the moving jaw is readily changed by adjustment of the toggle-abutment, and breakage of the parts by tools, bolts or other metal objects inadvertently fed into the machine with the material to be crushed, is avoided by a yielding movement of the stationary jaw against the pressure of the tension springs 25 which have previously been 100 adjusted by rotation of the nuts 28, to oppose the crushing pressure only.

105 In large power plants it frequently occurs that both lump and slack coal are delivered from the mine at one time, the slack coal being of sufficient fineness to pass to the furnaces without crushing.

110 In order to avoid the installation of different conveying means for the fine coal or the removal of the crushing machine while the fine coal is being conveyed to the bins, it is 115 essential that the crushing machine be capable of being converted into a chute for the conveyance of material without further comminution, and this is readily accomplished in the present machine by separating the 120

normally stationary jaw from the crushing roll through the medium of the racks and pinions after the dog has been lifted out of engagement with the teeth of the combined 5 hand and ratchet wheel.

The provision of a rapidly rotating crushing roll of small diameter permits of its 10 operation by direct connection with a motor or line shaft without the speed-changing gearing necessary in crushing machines in which the crushing roll is comparatively of large diameter.

Having thus described my improved 15 crushing machine I desire it understood that variations in details of construction and the arrangement of the parts thereof may be resorted to within the spirit of my invention as defined in following claims:

1. A crushing machine of the character 20 described comprising a frame, a rotary crushing roll, means for its rotation, eccentrics moving in conjunction with the roll, a normally stationary jaw extending upwardly from the roll, a loose jaw opposite the other, 25 having an operative connection with said eccentrics, and an oscillatory connection between the upper portion of the loose jaw and the frame.

2. A crushing machine of the character 30 described comprising a frame, a rotary crushing roll, eccentrics moving in conjunction therewith, a normally stationary jaw extending upwardly from the roll, a loose jaw opposite the other having an operative 35 connection with said eccentrics, and a toggle between the upper portion of the loose jaw and the frame.

3. A crushing machine of the character 40 described comprising a frame, a rotary crushing roll, eccentrics moving in conjunction therewith, a normally stationary jaw extending upwardly from the roll, a loose jaw opposite the other having an operative 45 connection with said eccentrics, and an adjustable toggle between the upper portion of the loose jaw and the frame.

4. A crushing machine of the character 50 described comprising a frame, a rotary crushing roll, eccentrics moving in conjunction therewith, a normally stationary jaw extending upwardly from the roll, a loose jaw opposite the other having an operative 55 connection with said eccentrics, a toggle between the upper portion of the loose jaw and the frame, and a spring holding the jaw in contact with the toggle.

5. A crushing machine of the character 60 described comprising a frame, a rotary crushing roll, eccentrics moving in conjunction therewith, a normally stationary jaw extending upwardly from the roll, a loose jaw opposite the other having an operative 65 connection with said eccentrics, a toggle between the upper portion of the loose jaw and the frame, a rod pivoted on the jaw, an

abutment plate adjustable on the rod, and a spring between said plate and the frame to hold the jaw in contact with the toggle.

6. A crushing machine of the character 70 described comprising a frame, a rotary crushing roll, eccentrics moving in conjunction therewith, a normally stationary jaw extending upwardly from the roll jaw, a loose jaw opposite the other having an operative connection with said eccentrics, an abutment adjustable on the frame, a toggle between the abutment and the upper portion of the loose jaw, and a spring to hold the jaw in connection with the toggle. 75

7. In a crushing machine of the character 80 described, a frame, a rotary crushing roll, two jaws providing together a passage for material to the roll, one of said jaws having at its upper end a pivotal connection with the frame, a rack connected at the lower portion of the pivoted jaw, a rotary pinion meshing with the rack, and means for holding the pinion against rotation. 85

8. In a crushing machine of the character 90 described, a frame, a rotary crushing roll, two jaws providing together a passage for material to the roll, one of said jaws having at its upper end a pivotal connection with the frame, a longitudinally movable rack, a yieldable connection between the rack and the lower portion of the pivoted jaw, a rotary pinion meshing with the rack, and means for holding the pinion against rotation. 95

9. In a crushing machine of the character 100 described, a frame, a rotary crushing roll, two jaws providing together a passage for material to the roll, one of said jaws having at its upper end a pivotal connection with the frame, and provided at its lower end with an apertured lug, a rod passing through said lug, a nut on the rod engaging the lug at one side thereof, a spring engaging the lug at the opposite side, an abutment on the rod engaging the spring, 105 a rack on the rod, a rotary pinion meshing with the rack, and means for holding the pinion against rotation. 110

10. In a crushing machine of the character 115 described, a frame, a rotary crushing roll, two jaws providing together a passage for material to the roll, one of said jaws having at its upper end a pivotal connection with the frame, a rod having a longitudinal movement on the lower portion of the pivoted jaw, a spring arranged to yieldingly oppose said movement, a rack on the rod, a rotary pinion meshing with the rack, and means to hold the pinion against rotation. 120

11. In a crushing machine of the character 125 described, a frame, a rotary crushing roll, two jaws providing together a passage for material to the roll, one of said jaws having at its upper end a pivotal connec- 130

tion with the frame, a rack connected at the lower end of the pivoted jaw, a rotary pinion meshing with the rack, a combined hand and ratchet wheel in connection with 5 the pinion, and a pawl acting upon the ratchet wheel to hold the pinion against rotation.

12. A crushing machine of the character described, comprising a frame, a rotary 10 crushing roll, a stationary jaw extending upwardly from the roll adjacent the periphery thereof, a loose jaw opposite the other, eccentrics supporting the loose jaw at its lower end and a toggle between the opposite 15 end of the same and the frame.

13. A crushing machine of the character described comprising a frame, a rotary crushing roll, a normally stationary jaw extending upwardly from the roll contiguous 20 to the lower portion thereof, and a moving jaw co-operating with the stationary jaw for the diminution of material between them and having its lower end spaced from the lower portion of the same to provide a passage 25 for material fed between the jaws, to the crushing roll.

14. A crushing machine of the character described comprising a frame, a pair of downwardly converging crushing jaws one

of which has a reciprocating movement with 30 relation to the other, the lower end of the reciprocating jaw being separated from the face of the other jaw to form a narrow throat for the passage of comminuted material, and the other, relatively stationary 35 jaw being extended below said throat to provide a surface for the further diminution of the material, and a rotary crushing roller disposed to act upon the material passing across said surface. 40

15. A crushing machine of the character described comprising a frame, a pair of downwardly converging crushing jaws one of which has a reciprocating movement 45 with relation to the other, the lower end of the reciprocating jaw being separated from the face of the other jaw to form a narrow throat for the passage of comminuted material, and the other, relatively stationary 50 jaw being extended underneath said throat to provide a surface at an angle to its working face for the further diminution of the material, and a rotary crushing roller disposed to act upon the material passing across 55 said surface.

In testimony whereof I have affixed my signature.

DAVID J. NEVILL.
